WELL REAMER

Charles J. Maher, Los Angeles, Calif.

Application November 9, 1934, Serial No. 752,299

13 Claims. (Cl. 255—73)

This invention relates to a well tool and relates more particularly to a well reamer for use in the rotary method of well drilling. A general object of the invention is to provide a simple, practical and particularly effective and efficient well reamer.

Another object of the invention is to provide a well reamer characterized by an oscillatory or gyratory cutter surrounding the reamer shank and having cutting parts for acting on the wall of the well bore, the cutting edges of said parts travelling in a path partially bounding or defining a sphere whose axis is in the axis of rotation of the reamer shank. The cutting parts having their active edges travelling in a spherical plane or course have active cutting engagement with the wall of the well bore at spaced points throughout its circumference to make the bore smooth and ream it to a uniform full gauge.

Another object of the invention is to provide a well reamer including an annular cutter surrounding the reamer shank and a novel and particularly effective anti-friction retaining means mounting the cutter on an axis inclined with respect to the axis of rotation of the shank, whereby the shank and cutter are related for relative rotation.

Another object of the invention is to provide a well reamer embodying a cutter in the form of a collar or tubular part of considerable longitudinal extent surrounding the reamer shank at an angle thereto and the shank and cutter being related for relative rotation.

Another object of the invention is to provide a well reamer of the character mentioned in which the gyratory cutter has novel teeth or cutting parts which have a clawing or digging action in engaging the formation at the wall of the well bore.

Another object of the invention is to provide a well reamer of the character mentioned in which the cutter may be easily and quickly arranged on and removed from the shank without disconnecting parts of the shank whereby the shank may be a simple, integral part or member.

A further object of the invention is to provide an improved well reamer embodying a minimum number of simple, sturdy, inexpensive parts.

The various objects and features of my invention will be fully understood from the following detailed description of a typical form and application of the invention, throughout which description reference is made to the accompanying drawing, in which:

Fig. 1 is a side elevation of the reamer provided by this invention. Fig. 2 is a view similar to Fig. 1 illustrating the lower portion of the shank and the cutter and its mounting in central longitudinal cross section. Fig. 3 is a transverse detailed sectional view taken substantially as indicated by line 3—3 on Fig. 1. Fig. 4 is an enlarged fragmentary detailed sectional view of a portion of the shank and a portion of the cutter illustrating the cutter mounting and retaining means. Fig. 5 is a view similar to Fig. 4 illustrating a slightly modified form of cutter tooth.

The reamer of the present invention includes, generally, a body or shank 10 adapted to be connected or interposed in a drilling string, a cutter 11 surrounding the shank 10 and disposed at an angle thereto, and means 12 rotatably mounting and retaining the cutter 11 on the shank 10.

The body or shank 10 constitutes a carrier or support for the cutter 11 and is adapted to be connected in a drilling stem or drilling string to form a part thereof. In accordance with the invention the shank 10 may be a simple integral elongate member as illustrated in the drawing. The shank 10 is provided at its opposite ends with means for facilitating its connection in the drilling string. In the case illustrated in the drawing a tapered screw-threaded pin 13 is provided on the upper end of the shank and a tapered socket 14 is provided in the lower end of the shank for connecting it in the well drilling string. A central longitudinal fluid passage 15 extends longitudinally through the shank 10 from one end to the other to pass or conduct the circulation fluid usually employed in the rotary method of well drilling.

The shank 10 is provided with a bearing or collar portion 16 for carrying or supporting the cutter 11. The portion 16 is suitably spaced between the ends of the shank 10 and preferably of substantial diameter. The cutter carrying shank portion 16 is generally cylindrical and its central longitudinal axis A is inclined with respect to the longitudinal axis B of the shank. It is preferred to have a downwardly facing thrust shoulder 17 at the upper end of the cutter supporting portion 16. With the portion 16 pitched or inclined as described above a downwardly facing shoulder 17 occurs at the upper end of the portion at one side of the shank 10. The opposite side of the shank 10 may be thickened or provided with a flange 18 whose lower end forms a continuation of the shoulder 17. The thrust shoulder 17 is thus continuous or annular and is preferably normal to the inclined axis A.

An enlargement 20 may be provided on the shank 10 where the lower end of the portion 16 extends outwardly beyond the major portion of the shank. The enlargement 20 is preferably provided with a substantially spherically curved surface which joins the cylindrical surface of the portion 16. A recess 21 occurs in the surface of the shank 10 at the lower end of the portion 16 and is diametrically opposite the enlargement 20.

10 The cutter 11 is rotatably supported and retained on the shank portion 16 by the means 12 to have its longitudinal axis A inclined relative to the longitudinal axis B of the shank. In accordance with the invention the cutter 11 includes an annular or tubular body 22 surrounding the shank portion 16. The longitudinal opening 23 in the cutter body 22 is concentric with the longitudinal axis of the said body and has a cylindric wall. The diameter of the opening 23 is somewhat greater than that of the shank portion 16 for the purpose to be hereinafter described. While the cutter body 22 may be shaped as found most desirable it may have its external surface substantially spherically curved as illustrated in the drawing.

15 The invention provides novel and improved teeth or cutting parts 24 on the cutter body 22. The cutting parts 24 project outwardly from the external surface of the cutter body 22 and in the case illustrated are integrally joined with the body of the cutter. The cutting parts 24 are preferably independent of one another and arranged in rows. The rows of cutting parts 24 are spaced circumferentially one from the other and extend between the upper and lower ends of the cutter body 22. The rows of cutting parts 24 are pitched or inclined downwardly and forwardly relative to the direction of rotation of the reamer shank 10. The individual cutting parts 24 of the rows are offset or staggered vertically and circumferentially of the cutter body 22. The adjacent cutting parts 24 of the rows may be in close proximity to one another. In the particular case illustrated in the drawing the lower forward corner of a cutting part 24 is immediately adjacent the upper rear corner of the adjoining or adjacent part 24. The outer surfaces 25 of the cutting parts 24 are inclined or curved downwardly and outwardly from the cutter body 22. The lower ends or surfaces 26 of the cutting parts 24 may be flat and substantially normal to the axis A as shown in Figs. 1, 2, and 4. However, it may be preferred to curve the lower surfaces of the cutting parts upwardly and inwardly to the body of the cutter as shown at 26a in Fig. 5. The outer surfaces 25 and the lower surfaces 26 join at cutting edges 27. The cutting teeth or parts 24 may be of downwardly increasing thickness. For example, their ends or sides which face rearwardly relative to the direction of rotation of the reamer may be inclined downwardly and rearwardly as disclosed in the drawing.

20 It is an important feature of the invention that the cutting edges 27 of the several cutting parts 24 travel in a spherical plane or path or a path partially defining or bounding a sphere. The cutting parts 24 are formed and proportioned so that their edges 27 are equally spaced from a common point P in the central longitudinal axis A of the cutter 11. In practice the point P constituting the axis of the spherical path of movement of the cutting edges 27 occurs at or 25 is coincident with the point of intersection of the

axis A and B. Where the external surface of the cutter body 22 is not spherically curved about the point P the cutting parts 24 may vary somewhat in size to have their cutting edges 27 equidistant from the point P. In other respects the plurality of cutting teeth 24 may be alike in size. The upper cutting parts 24 occur at or adjacent the upper end of the cutter body 22, for example, they may project downwardly and outwardly from the upper end of the cutter body. The lowermost cutting parts 24 are preferably positioned so that their cutting edges 27 are in or adjacent the plane of the lower end of the cutter body 22. The action or operation of the cutter 11 and its cutting parts 24 will be hereinafter set forth in full in the description of operation of the reamer.

The means 12 relates the cutter 11 and the shank 10 for relative rotation and provides or includes annular grooves 28 in the shank portion 16. The grooves 28 are partially circular or partially spherical in transverse cross section and are spaced from the upper and lower ends of the shank portion 16. Correspondingly shaped annular grooves 29 are provided in the wall of the opening 23 in the cutter body 22. The grooves 29 are spaced and positioned to directly oppose the grooves 28. Series of balls 30 are arranged in the two pairs or sets of grooves 28 and 29. The balls 30 support the cutter 11 on the shank 10 and cooperate with the grooves 28 and 29 to hold the cutter against longitudinal movement and displacement from the shank portion 16. The parts are related so that the wall of the opening 23 is spaced a considerable distance from the surface 30 of the shank portion 16 providing an annular space for holding lubricant. Openings 31 are provided in the wall of the cutter body 22 to allow the balls 30 to be placed in the registering or opposing grooves 28 and 29. The openings 31 40 are normally closed by plugs 32.

Means may be provided for sealing the opposite ends of the space between the wall of the cutter opening 23 and the surface of the shank portion 16 to retain the lubricant in the space and to prevent the accumulation therein of cuttings and solid matter. A packing or sealing assembly is provided in each end portion of the cutter opening 23. Each of said assemblies includes two split rings 33 and a continuous or unbroken packing ring 34 between the pair of rings 33. The packing rings 34 may be formed of rubber or the like and are adapted to seal with the wall of the opening 23 and the surface of the shank portion 16. The shoulder 17 on the shank 10 of course 55 prevents displacement of the upper packing assembly. The two rows or series of balls 30 limit the inward movement of the packing assemblies. Means is provided for holding the lower packing assembly against downward displacement from 60 between the cutter body 22 and the shank portion 16. A resilient snap ring 35 is sprung or pressed into a groove 36 in the wall of the opening 23 to cooperate with the wall of a groove 37 in the lower split ring 33. The snap ring 35 effectively 65 prevents loss or displacement of the lower packing assembly.

In operation the shank 10 is interposed or connected in the drilling string so that the reamer operates in the desired position or zone in the well. As the drilling string is rotated and fed downwardly in the usual manner the cutting parts 24 act on or engage the formation at the side wall of the well bore. The cutter 11 being rotatably supported on the shank 10, the engage- 75

ment of the cutting parts 24 with the formation holds or tends to hold the cutter against turning with the shank. The cutter 11 rotatably supported on the shank 10 by the means 12 is retained in an inclined position with relation to the shank and when it lags or is held against turning it is given a gyratory motion. In other words, during rotation of the drilling string any given point on the cutter 11 or any given cutting part 24 gyrates and the center or axis of this motion is the point P. The cutting parts 24 are thus given both horizontal and vertical movement with respect to the shank 10.

The rows of staggered teeth or cutting parts 24 are moved upwardly in a rotary manner and then moved downwardly in a similar manner with respect to the shank 10 as the shank rotates relative to the cutter 11. As a row of staggered cutting parts 24 moves downwardly in a somewhat curved path the cutting parts of the row are progressively or successively brought into active engagement with the wall of the well bore. The cutting edges 27 of the cutting parts 24 are equally spaced from the point P and move in a spherical path indicated at X in Fig. 1 of the drawing. As the row of teeth 24 moves downwardly as above described the cutting edges 27 successively cut into the wall of the well bore as they approach and reach the line of intersection or joinder of the spherical path X and the wall of the bore. The cutting parts 24 are preferably proportioned so that one cutting part 24 of a row bites into the formation as a lower adjacent cutting part leaves or moves out of contact with the formation. The adjacent higher cutting part 24 is also advancing into contact with the formation and in this manner each row of cutting parts 24 has at least one of its number in active engagement with the formation.

The cutting parts 24 arranged in downwardly and forwardly inclined rows progressively move or swing across a given portion of the wall of the well bore and being staggered do not track in their action on the formation. Due to their configuration and their gyratory movement the cutting parts 24 bite or dig into the formation to effectively cut away the same. Because the cutting edges 27 of the cutting parts 24 move in the spherical path X a plurality of cutting parts 24 are in active cutting engagement with the wall of the well bore at circumferentially spaced points. The rows of cutting parts 24 are equally spaced around the cutter 11 so that these points of active contact of the cutting parts with the wall of the bore are equally spaced around the wall of the bore. Following the downward and forward progression or movement of a row of cutting parts 24 the gyratory motion imparted to the cutter 11 by the rotary motion of the shank 10 moves the row of cutting parts 24 rearwardly and upwardly until they again move downwardly and forwardly. The digging action of the cutting parts 24 is particularly efficient in removing the formation at the side wall of the bore. The cutting edges 27 of the cutting parts travelling through the spherical path X engage the wall of the well bore at spaced points throughout its circumferential extent as distinguished from disc-like annular cutters, rotatable about axes inclined relative to a shank, which disc-like cutters can only have active engagement with the formation at diametrically opposite points. The reamer of the present invention is particularly steady and smooth in its operation because of the engagement of its cutting parts 24 with the wall of the bore at

equally spaced points. The spaces between the rows of cutting parts 24 constitute channels for freely passing the upwardly flowing circulation fluid in the well bore so that the cutter 11 does not materially obstruct the flow through the well. The anti-friction retaining means 12 is such that the engagement of the cutting parts 24 with the formation in most instances holds the cutter against turning with the shank so that the cutting parts have the desired gyratory motion and cutting action.

In assembling the cutter 11 on the shank 10 the body 22 of the cutter may be freely passed over the lower portion of the shank until it reaches a position where one side portion is received in the recess 21 and the opposite side portion is at the enlargement 20. The cutter body 22 may be tipped relative to the shank 10 as it enters the recess 21 so that it may be swung or pivoted over the spherically curved enlargement 20 to the inclined position where it surrounds the shank portion 16. It is believed that it will be clear how the series of balls 30 may be arranged in the grooves 28 and 29 and how the packing assemblies may be positioned in the opposite ends of the cutter opening 23. As the cutter 11 may be readily passed over the end portion of the shank 10 to its position around the portion 16, the shank 10 may be a simple integral member as illustrated in the drawing.

Having described only a typical preferred form and application of my invention I do not wish to be limited or restricted to the specific form and application herein set forth, but wish to reserve to myself any modifications or variations that may appear to those skilled in the art or fall within the scope of the following claims.

Having described my invention, I claim:

1. A well reamer including a shank adapted to be connected in a drilling string, a cutter surrounding and rotatably supported on the shank, and circumferentially and vertically spaced cutting parts on the cutter adapted to operate in a path constituting a portion of a sphere and simultaneously contact the wall of the well bore at spaced points throughout its circumference.

2. A well reamer including a shank adapted to be connected in a drilling string, a cutter surrounding the shank and having an axis inclined with respect to the axis of rotation of the drilling string, and circumferentially spaced rows of cutting parts on the cutter having cutting edges which operate in a path forming a portion of a sphere and which simultaneously contact the wall of the well bore at spaced points throughout its circumference.

3. A well reamer including a shank adapted to be connected in a drilling string, an annular cutter surrounding the shank and having a substantial longitudinal dimension relative to its diameter, circumferentially spaced rows of vertically spaced teeth on the cutter, and means rotatably supporting the cutter on the shank with its axis inclined relative to the axis of rotation of the string whereby the cutter is operable to simultaneously act on the wall of the well at diametrically opposite points.

4. A well reamer including a shank having means at its opposite ends for connecting it in a drilling string, a cutter surrounding the shank and having its axis inclined relative to the axis of rotation of the drilling string, the shank and cutter being related for relative rotation, and circumferentially and vertically spaced cutting parts on the cutter operable to simultaneously

act on the well bore at spaced points throughout its circumference.

5. A well reamer including a shank adapted to be connected in a drilling string, a cutter surrounding and rotatably arranged on the shank with its axis inclined relative to the axis of rotation of the drilling string, and circumferentially spaced inclined rows of cutting parts on the cutter having cutting edges which operate in a path constituting a circumferential portion of a sphere and simultaneously act on the wall of the well at spaced points throughout its circumference.

6. A well reamer including a shank having means at its opposite ends for connecting it in a drilling string, a cutter surrounding and rotatably mounted on the shank with its axis inclined relative to the axis of rotation of the drilling string, and circumferentially and longitudinally staggered cutting parts on the cutter operable to simultaneously act on the wall of the well at spaced points throughout its circumference.

7. A well reamer including a shank, means on the opposite ends of the shank for connecting it in a drilling string, a cutter surrounding and rotatably arranged on the shank with its axis inclined relative to the axis of rotation of the drilling string, and circumferentially spaced rows of vertically spaced teeth on the cutter.

30 8. A well reamer including a shank, means at the opposite ends of the shank for connecting it in a drilling string, a cutter surrounding the shank and rotatably retained thereon to have its axis inclined relative to the axis of rotation of the drilling string, and circumferentially spaced rows of longitudinally and circumferentially staggered cutting parts on the cutter, the cutting parts of said rows being staggered circumferentially in a forward direction relative to the direction of rotation of the drilling string.

40 9. A well reamer including a shank having threads at its opposite ends whereby it is adapted to be interposed in a drilling string, said reamer being characterized by a gyratory cutter surrounding the shank and including a plurality of rows of vertically and circumferentially offset teeth having cutting edges operating in a path

forming a portion of a sphere whose center is in or adjacent the longitudinal axis of the shank.

10. A well reamer including a shank, means at the opposite ends of the shank for connecting it with a drilling string, a cutter surrounding and rotatably supported on the shank to have its longitudinal axis inclined with respect to the longitudinal axis of the shank, and circumferentially spaced rows of vertically and circumferentially staggered cutting parts on the cutter, 10 the cutting parts having lower outer cutting edges operating in a path constituting a circumferential portion of a sphere.

11. A well reamer including a shank, means at the opposite ends of the shank for connecting it with a drilling string, a cutter surrounding and rotatably supported by the shank to have its axis inclined with respect to the longitudinal axis of the shank, and projecting cutting parts on the cutter for simultaneously acting on the wall of the well at spaced points throughout its circumference, the cutting parts having downwardly and outwardly inclined upper sides and undercut lower sides joining at cutting edges operating in a path which constitutes a circumferential portion of a sphere.

12. A well reamer including a shank, means at the opposite ends of the shank for connecting it with a drilling string, the shank having a portion whose longitudinal axis is inclined with respect to the longitudinal axis of the shank, a downwardly facing thrust shoulder at the upper end of said portion, and a cutter rotatable on said portion and having parts simultaneously acting on the wall of the well at spaced points throughout its circumference.

13. A reamer including, a generally cylindrical body having an annular integral collar portion disposed at an inclination to the vertical axis of the body, an annular groove in said integral collar portion, an annular cutter member having an internal annular groove coinciding with the annular groove in the collar portion, and a series of bearing balls in said coinciding annular grooves of the collar portion and cutter member.

CHARLES J. MAHER.
